TRAY RACK

Denis J. Stenamie, Williamson, N.Y., assignor to
Xerox Corporation, Stamford, Conn.

Continuation-in-part of design application Ser. No.
319,834, Dec. 29, 1972, now Patent No. 336,036.
This application Sept. 16, 1974, Ser. No. 506,383

Term of patent 14 years

Int. Cl. D16—05; D18—99
U.S. Cl. D16—32

FIG. 1

FIG. 2

FIG. 3

FIG. 4

FIG. 5

FIG. 1 is a front elevational view of a tray rack showing my new design;

FIG. 2 is a rear elevational view thereof;

FIG. 3 is a top plan view thereof;

FIG. 4 is a left side elevational view thereof; and

FIG. 5 is a right side elevational view thereof.

This is a continuation-in-part of design application Ser. No. 319,834, filed Dec. 29, 1972, now Patent Des. 236,030.

I claim:

The ornamental design for a tray rack, as shown.
